UNITED STATES PATENT OFFICE.

HERBERT R. WESTOVER, OF AMESBURY, MASSACHUSETTS, ASSIGNOR TO HAMEL SHOE MACHINERY COMPANY, A CORPORATION OF MASSACHUSETTS.

SHOE-COATING MACHINE.

1,366,441.

Specification of Letters Patent. Patented Jan. 25, 1921.

Application filed September 25, 1918. Serial No. 255,668.

To all whom it may concern:

Be it known that I, HERBERT R. WESTOVER, a citizen of the United States, residing at Amesbury, in the county of Essex and State 5 of Massachusetts, have invented certain new and useful Improvements in Shoe-Coating Machines, of which the following is a specification, reference being had therein to the accompanying drawings.

10 This invention relates to shoe machines and more specifically to machines for applying a fluid such as coloring ink or cement to the surface of shoe soles.

In the manufacture of turn and McKay 15 shoes it is customary to treat the outersole preparatory to attaching the same to the upper by applying blacking or color to the upper or flesh surface of the sole adjacent the outer edge thereof, as it is difficult in 20 these types of shoe to color this edge, which projects beyond the upper, after the attachment of the upper to the same, owing to the narrowness of the crease between the edge of the sole and the upper. This operation is 25 usually performed by hand, the operator using for this purpose a brush,—commonly an ordinary tooth brush, which he dips into a pan of ink and then applies by a continuous motion to the surface of the sole adjacent the 30 edge and following the contour of the same. This mode of applying the color necessarily consumes a considerable amount of time, as the operator is obliged to move his brush along the edge of the sole throughout its 35 entire extent.

The present invention comprises mechanism adapted to apply fluid to the surface of a shoe sole simultaneously along its opposite lateral edges, thus securing a high 40 speed of operation, said mechanism including a pair of independent, oppositely disposed fluid-applying devices arranged to move toward and away from each other in following the contour of the sole, but to move into close proximity to each other 45 whereby to form in effect a single centrally disposed fluid-applying device in operating upon the heel and toe portions of the sole.

The invention further consists in the provision of means for so guiding the fluid-applying devices that they are caused to closely follow the contour of the sole edge, thereby insuring application of the fluid throughout the extent of the edge while avoiding daubing of the other parts of the sole.

The invention consists further in the provision of feeding means for moving the soles relatively to the fluid-applying devices.

The invention further contemplates the employment of suitable means for guiding 60 the sole into proper relation to the feeding and fluid-applying devices.

Another feature of the invention resides in the provision of adjusting means for the feeding devices whereby to compensate for 65 wear of the parts which may be occasioned during their continued operation, as well as for variations in the character of the material operated upon.

The invention also embodies improved 70 drive mechanism whereby the various operative elements are moved at suitable relative velocities, and whereby the fluid-applying devices are permitted to move freely in following the sole edge, such mechanism 75 comprising a shaft having a collapsible section permitting variations in the effective length of such shaft.

Other and additional objects and advantages together with improved combinations 80 of parts and details of construction will be hereinafter pointed out and distinctly claimed, reference being had to the annexed drawings for a complete disclosure of a preferred form of the invention and in which— 85

Figure 1 is a plan view of the machine;

Fig. 2 is a vertical section through the axes of shafts upon which are mounted pulleys 17, 18, Fig. 1;

Fig. 3 is a central vertical transverse section to larger scale taken at the normal plane of contact of brushes 89, 90 (Fig. 1);

Figs. 4, 5 and 6 are a series of diagrammatic views illustrating the operation of the machine.

1 indicates the main frame of the machine which is supported upon legs 2, the lower portions of which may be provided with outstanding flanges 3, if desired, whereby the same may be secured to the floor or other 100 suitable support. 4, 4^a indicate bars connecting the forward and rear legs of the frame and serving to support a pair of saddle-like members 5, 5^a, respectively, these members providing journal openings for a 105 main shaft 6, the ends of which extend outwardly beyond said members 5, 5^a. Upon one extremity of the shaft 6 is fixed a drive pulley 7 of ordinary form and between said pulley and the member 5^a is fixed a grooved 110

pulley 8 of relatively small diameter. Upon the opposite extremity of the shaft is fixed a grooved pulley 9 similar to the pulley 8. Fixed to the shaft 6 between the members 5, 5^a, and spaced apart from each other, are grooved pulleys 10 and 11, said pulleys being of larger diameter than pulleys 8 and 9.

Upon the upper surface of the frame 1 and near the respective lateral edges of the same are mounted a pair of upstanding brackets 13, 14 which may be secured to the frame 1 by means of bolts 12 or equivalent devices. Journal openings are provided in the brackets 13, 14, said openings being in alignment, and within said openings are rotatably mounted shafts 15, 16, said shafts having fixed upon their extremities, which project outside said brackets 13, 14, grooved pulleys 17, 18 of a diameter relatively small as compared to that of the pulleys 10 and 11. Belts 19, 20 connect the respective pairs of pulleys 8, 17,—9, 18, whereby the shafts 15, 16 may be continuously driven in the same direction upon rotation of shaft 6.

Fixed upon the forward portion of the upper surface of frame 1 and upstanding therefrom are a pair of brackets 21 secured to said frame in any suitable manner. These brackets at their upper portions are bifurcated to form spaced guide members 21^a, 21^b, between which are slidably mounted pairs of blocks 22, 22,—23, 23, said blocks being provided with journal openings in which are mounted a pair of feed rolls 24, 25. The upper roll 24 projects through bearing block 22 at its left hand extremity, as viewed by the operator, and has fixed upon it, outside of said bearing, a grooved pulley 26 having driving connection by means of an open belt 28 with the pulley 10 on shaft 6. The roll 25 extends beyond its right hand bearing in block 23 and has fixed thereon outside said block, a grooved pulley 27, this pulley being connected by means of a crossed belt 29 with the pulley 11 on the shaft 6. By the above described arrangement of belts, it will be seen that the rolls 24, 25 are rotated in opposite directions. The blocks 23, when in position, rest upon cross bars 30 of the brackets 21.

Extending upwardly from the blocks 22 are rods 31 which pass through openings in cross bars 32 connecting the upper portions 21^a, 21^b of the brackets 21, said rods 31 having nuts 33 screw-threaded upon their upper extremities,—springs 34 being interposed between the upper surfaces of said blocks 22 and the under surfaces of cross bars 32, this arrangement of parts permitting the upper roll 24 to move away from roll 23 against the tension of the spring 34 to accommodate soles of varying thickness.

35 are lugs projecting forwardly from the brackets 21 and serving to support a work table 36, upon the upper surface of which are

provided guide members 37, 38. These guide members converge in such a manner as to direct a shoe sole to the center part of the rolls 24, 25 when such sole is moved toward said rolls by the hand of the operator.

Projecting rearwardly from the respective brackets 21 are a pair of lugs 39 which serve to support a second work table 40 located in the rear of the rolls 24, 25. 41 are pins projecting upwardly from said work table 40 at its corners and serving to guide a work hold-down plate 42, the latter having openings therein adapted to take over the rods 41 whereby plate 42 is guided for vertical movement relatively to table 40. The pins 41 are screw-threaded at their upper extremities for the reception of thumb nuts 43, and located between said nuts and the upper surface of the plate 42 are coiled springs 44. If desired, washers may be placed upon the pins 41 and interposed between the plates 40 and 42 to hold said plates in normally spaced relation.

Fixed to the upper portions of the brackets 13, 14 are standards 45, 46, said standards being provided with substantially flat upper surfaces, over which swing bracket members 49, 50, said members being pivoted to the standards 45, 46 as by means of bolts 47, 48. The upper surfaces of the standards 45, 46 are provided with pairs of upstanding stop members 51, 52,—53, 54, respectively, these members serving to limit the swinging movement of the brackets 49, 50. 55, 56 are supports mounted upon the upper surface of the main frame 1 and providing substantially horizontal supporting elements 57, 58, underlying the brackets 49, 50 and serving to guide the same in their swinging movements. The supports 55, 56 are also provided with forwardly extending fingers 102, 103, to which are connected coiled springs 49^a, 50^a, the other extremities of which are suitably connected to the respective brackets 49, 50, said springs serving normally to resiliently hold said brackets 49, 50 against the stop members 51, 53, respectively.

Brackets 49, 50 are provided with pairs of downwardly extending legs 59, 60,—61, 62, respectively, said legs providing at their lower extremities alined bearing openings in which are mounted shafts 63, 64, these shafts being adapted to rotate and also to slide axially in said bearings. The legs 59, 60,—61, 62 are also provided with openings in which are slidably arranged rods 65, 66 parallel to the shafts 63, 64, these rods where they pass through the legs 60, 62, respectively, being squared to prevent rotation of said rods about their own axes, springs 69, 70 being interposed between said squared portions of the rods and the adjacent surfaces of the legs 59, 61. It will be noted that by this arrangement of parts

the rods 65, 66 tend to slide toward one another in their bearings.

The adjacent extremities of the rods 65, 66 are bifurcated to form spaced arms 71, 72 between which are mounted guide rolls 73 adapted to turn freely on vertical axes. 75 Yoke members 75 are yoke members fixedly connected to the squared portions of the shafts 65, 66, as by means of screws 74, said yoke members 10 having slotted engagement with shafts 63, 64, at their lower extremities and being located between pairs of collars 76, 77 fixedly secured to the respective shafts 63, 64. By this arrangement of parts any sliding movement 15 imparted to the rods 65, 66 will be transmitted to the shafts 63, 64, which will thereby be caused to slide axially in their bearings.

98, 99 are pins upstanding from the members 71 of the rods 65, 66 and having connected thereto one end of chains 100, 101, respectively, the other ends of said chains being connected to the fingers 102, 103 extending from supports 55, 56, respectively. 25 As will be noted the length of the chains 100 and 101 is less than the distance between the point of connection of said chains to the rods 65, 66, and the pivot members 47, 48 of brackets 49, 50.

30 78, 79 indicate universal joints of ordinary construction having the driving elements thereof connected respectively to the inner extremities of shafts 15 and 16. 80, 81 indicate generally a pair of collapsible 35 and extensible connector devices interposed in the driving connections for shafts 63, 64, said connector devices each comprising disks 82, 83 fixed respectively upon the ends of said shafts 63, 64 and to the driven elements of the universal joints 78, 79. Hingedly connected to each of the disks 82, 83 is a series of link members 84, 85, in the present embodiment there being four of such links connected to each of the collars 40 and spaced equally about the peripheries of the same. The respective links of the two series form complementary pairs whose free extremities are pivotally connected together at 86. This arrangement of parts serves to 45 transmit the rotary motion of the shafts 15, 16 to the shafts 63, 64, respectively, while at the same time permitting longitudinal sliding movement of the shafts 63, 64 in their bearings, the universal joint connections between said shafts 15, 16 and shafts 63, 64 50 also permitting a swinging movement of the latter in a horizontal plane.

Upon the adjacent extremities of shafts 63, 64 are fixed flanges 87, 88 serving to support a pair of fluid-applying brushes 89, 90 which may be secured to said flanges in any suitable manner. In the normal position of the parts as shown in Figs. 1 and 2, it will be seen that the peripheral surfaces of said 65 brushes which are of the same diameter,

form in effect a single brush surface. 91 is a reservoir for containing fluid, such as coloring ink or cement, said reservoir being removably supported upon blocks 92 resting upon the upper surface of the frame 1. The 70 reservoir is provided at 93 with a shield or cover closing the rear portion of the same, and thereby preventing the accidental dropping of shoe soles into the liquid contained therein. As will be clearly seen from inspection of Figs. 2 and 3, the lower portion of the brushes dip into the fluid contained in said reservoir, and as such brushes are rotated they take up fluid from the reservoir and transmit it to the surface of a 80 shoe sole when the latter is placed in contact with said brushes.

94, 95 are upstanding brackets secured to the upper surface of the frame 1 and providing forwardly extending, overhanging 85 portions 96, having downwardly beveled forward extremities 97, said beveled extremities serving to direct the sole of a shoe in a downward direction after the latter has passed the brushes, whereby such sole is 90 prevented from being projected forcibly from the machine by the action of the feed rolls, but is caused to drop downwardly toward the shield 93.

The operation of the machine is substantially as follows reference being had to Figs. 4, 5, and 6 as indicating the various steps in the operation: The operator standing at the front of the machine places a sole with the flesh side thereof in contact with the upper 100 surface of the table 36, and between the guides 37, 38, and moves the same forwardly until the extremity is gripped between the feed rolls 24, 25, which at this time are being rotated in opposite directions and at a 105 relatively high speed. Upon engagement by the feed rolls, the sole is moved rapidly rearward toward the brush wheels 89, 90, passing between the plates 40, 42, the latter of which rises against the action of springs 110 44 to permit the passage of the sole beneath the same, the plate 42, however, serving to hold the sole downwardly and in position for substantially tangential contact with the upper portion of the brushes. 115

As the advancing end of the sole comes in contact with the brushes, which at this time are closely adjacent one another, and form in effect a unitary brush, fluid is applied to the sole surface near such extremity, 120 but as the sole continues to advance, the lateral edges thereof contact with the rolls 73 carried by the rods 65, 66, and by pressure thereagainst tend to swing said rods together with brackets 49, 50 about the pivot 125 bolts 47, 48, thus causing a separation of the brushes. This movement is clearly indicated in Fig. 4.

Owing to the great variation of the width of a sole from its toe to its heel portion it 130

has been found desirable to mount the brushes not only to swing about the pivot pins 47, 48, but also to slide with relation to the brackets 49, 50 in order that the plane of said brushes may be maintained as near in alignment with the edge of the sole as possible, but as at this time the sole is usually in temper, that is to say, more or less moist and has very little transverse rigidity, the 10 chains 100 and 101 have been provided which act immediately upon swinging of the brackets 49, 50 about their pivots to positively retract the rods 65, 66 within their bearings, thereby moving the brush wheels 15 89, 90 apart more rapidly than would be occasioned merely by their swinging movement (see Fig. 5).

As the sole is fed rearwardly over the brush wheels, the guide rolls 73 travel along 20 the outer edge of the sole, and cause the peripheral surfaces of the brush wheels which engage the lower surface of the sole to follow lines closely adjacent the edge thereof, thereby applying narrow strips or 25 ribbons of color to the surface of the sole following its contour. By reason of the independent mounting of the brush wheels, said wheels are enabled to follow the opposite edges of the sole, although said edges 30 are unsymmetrical.

As the sole is advanced, the rolls 73 in passing into the shank portion may permit the brackets to return to their initial position, the flexibility of the chain members, 35 however, permitting the slide rods 65, 66 together with the brushes to remain in partially retracted position relatively to the brackets during this portion of the operation. As the sole further advances the 40 brackets may again be caused to swing outwardly as the brushes pass along the heel, but as the extremity of the heel passes by the brushes the latter are again allowed to return to their normal position, whereby the 45 lateral lines of fluid are united to form a continuous strip.

It will be noted from the relative ratios of the pulleys employed for driving the feed rolls 24, 25, and the brush wheels 89, 90, that 50 the peripheral speed of the latter is smaller than that of the feed wheels, it being found undesirable to rotate the brushes at as high a speed as that of the feed rolls, as to do so tends to cause a spattering of the fluid. As 55 the advancing end of the sole passes the brush wheels, it is deflected downwardly by the beveled extremities to the brackets 94, 95, and is thereupon grasped by the operator who pulls the same rearwardly to 60 cause the necessary feed movement thereof during the latter portion of the action of the brushes thereon; the feed rolls 24, 25 cease to feed the sole along before the entire length thereof has been subjected to the 65 brushes. By reason of the adjustable mount-

ing of the upper feed roll, it is evident that the latter may be suitably positioned for use with stock of various thicknesses, and by the provision of the spring-pressed plate 42, it is clear that the advancing sole may be held 70 with more or less pressure in position for engagement with the surface of the brush.

While the above described mechanism is a preferred embodiment of the invention it is evident that various changes and modifications thereof might be made without departing from the essential characteristics of the invention, and it is contemplated that all such changes and modifications may be made as will fall within the scope of the appended 80 claims.

Having thus now described a preferred embodiment of the invention and the mode of operation thereof, what I claim and desire to secure by Letters Patent of the 85 United States is,—

1. In a machine of the class described, means for feeding a shoe sole in a substantially rectilinear path, a movable fluid-applying device, means normally acting to 90 move said device toward said path and a member actuatable in opposition to said means whereby to cause said applying device to follow the outer contour of the sole.

2. In a machine of the class described, a 95 rotatable fluid-applying device, a movable support therefor, and a guide member connected to said support for contact with the outer edge only of a sole, relative movement between said sole and guide member thereby 100 causing said applying device to follow the contour of the sole.

3. In a machine of the class described, means for feeding forward a shoe sole, a bodily movable, rotary fluid-applying device, and guiding means therefor arranged to contact with the edge only of a shoe sole 105 as it is fed forward.

4. In a machine of the class described, means for feeding a shoe sole in a substantially rectilinear path, and a fluid-applying device rotatable in a plane perpendicular to the sole surface and movable toward and from said path, and means for guiding said device to follow the contour of the shoe sole. 110

5. In a machine of the class described, a fluid supply and a plurality of fluid-applying devices rotatable upon substantially horizontal axes and constructed and arranged to apply fluid simultaneously to the 120 surface of a sole adjacent the opposite lateral edges thereof.

6. In a sole coloring machine, a pair of pivotally mounted bracket members, a pair of rotary color-applying devices carried by 125 the respective bracket-arms and normally adjacent one another, and contact elements carried by the respective bracket members and arranged for engagement with the opposite edges only of a shoe sole, whereby 130

movement of a sole between said elements acts to swing the bracket members and thereby separate said devices.

7. In a sole coloring machine a pair of oppositely directed, movably mounted supporting members, means acting normally to cause said members to approach one another, a pair of color-applying devices mounted upon the respective members, the operative portions of said devices being normally in alinement and forming in effect a single device, means for rotating said devices, and a pair of guides operatively connected to the respective members and arranged for engagement with the opposite edges of a shoe sole upon movement of the latter therebetween.

8. In a sole coloring machine, in combination, a pair of pivotally mounted bracket members, a pair of rotatable shafts carried by the respective members, a pair of color-applying brushes fixed upon the respective shafts, the operative portions of said brushes being normally in alinement and forming in effect a single continuous brush surface, means for constantly rotating said shafts, and a pair of spaced apart contact-rolls carried by the respective members and arranged for engagement with the edges of a shoe sole, whereby movement of a sole between said rolls acts to separate the brushes.

9. In a machine of the class described, a frame, a pair of bracket members pivoted thereon to swing in the same plane, said members being oppositely directed, resilient means normally holding said members in alinement, a pair of shafts carried by the respective members, means for constantly rotating said shafts, a pair of brush wheels fixed upon adjacent ends of the respective shafts, means for supplying said wheels with fluid, means for feeding a shoe sole over said brushes, and means actuatable to swing said brackets to thereby cause a separation of the brushes upon feeding movement of a shoe sole.

10. A machine of the class described, means for gripping and feeding a sole, a pair of fluid-applying devices arranged to contact with a sole while held by said gripping means, means for supporting said devices for movement toward and from one another, means normally moving said devices toward one another, and means for contact with the shoe sole during its feeding movement for separating said devices.

11. In a machine of the class described, in combination, means for feeding a shoe sole in a substantially rectilinear path, a pivotally mounted bracket, a supporting member slidably carried by said bracket and movable in a direction normal to the path of the sole, and a fluid-applying device mounted upon said member.

12. In a machine of the class described, means for guiding a shoe sole in a substantially rectilinear path, a device for applying fluid to the surface of a sole, said device being normally positioned adjacent said path, means for slidably and pivotally supporting said device, means for engagement with a shoe sole for swinging said device away from said path, and means for insuring sliding movement of said device away from said path simultaneously with such swinging movement.

13. In a machine of the class described means for feeding a shoe sole in a substantially rectilinear path, a pivotally mounted bracket, a supporting member slidable thereon in a direction normal to said path, a fluid-applying device carried by said member, means arranged for contact with the shoe sole upon feeding movement of the latter for swinging said bracket, and a device operatively connected to said supporting member and constructed to insure a sliding movement thereof with respect to the bracket upon swinging of the latter.

14. In a fluid-applying machine, in combination, a pair of brackets pivotally mounted to swing in the same plane, and being oppositely directed, normally aligned supporting members slidably mounted upon said brackets, ink-applying devices carried upon adjacent extremities of said members, means normally positioning said devices substantially in contact, a pair of roll-carrying members operatively connected to the respective members and provided with guide rolls arranged for contact with the opposite edges of a shoe sole, means for feeding a sole between said rolls thereby acting to swing said brackets in opposite directions and a pair of flexible elements, whose opposite extremities are connected with a fixed portion of the frame and with the respective roll-carrying members, respectively whereby upon swinging of the latter the supporting members are slidably retracted.

15. In a sole coloring machine, in combination, a frame member, a bracket pivoted thereto for oscillation about a substantially vertical axis, means for limiting such oscillation, a shaft journaled in said bracket and having its axis in a substantially horizontal plane, a color applying device mounted to rotate with said shaft, and means for constantly driving said shaft in all positions of pivotal adjustment of the bracket.

16. In a sole coloring machine, in combination, a frame member, a bracket pivoted thereto for oscillation about a substantially vertical axis, means for limiting such oscillation, a shaft journaled in said bracket, a color applying device fixed upon said shaft, a substantially horizontal drive shaft journaled in said frame and a universal joint connection between said shafts.

17. In a sole coloring machine, in combination, a support, a shaft journaled for rotation and for axial sliding movement in said support, a color-applying device fixed upon one extremity of said shaft, a drive shaft, and an extensible connection between said shafts.
18. In a machine of the class described, a shaft mounted for simultaneous rotation and axial sliding movement, a color-applying device fast to the shaft, a drive element alined with said shaft and a collapsible connection between said shaft and said element, said connection comprising a pair of disks fixed to said shaft and the element respectively, a series of link members hingedly connected to each of said disks, and circumferentially spaced about its periphery, the links of the respective series extending toward one another and forming complementary pairs, and pivotal connections between the opposed extremities of said pairs of links.
19. In a machine for applying fluid to shoe soles, a rotary fluid-applying device, means for feeding a sole into operative relation to said member, and means for driving said rotary device and said feeding means at substantially different relative peripheral velocities.
20. In a sole coloring machine, in combination, sole feeding and sole controlling means, a fluid-applying brush rotatable in a plane perpendicular to that of the sole surface, and means for rotating said brush in a direction opposite to that of the path of travel of the sole.
21. In a sole coloring machine, in combination, sole feeding rolls, sole controlling means, a pair of fluid-applying brushes, the axes of said rolls and brushes being normally substantially parallel, means for rotating said rolls, and means for rotating said brushes, the direction of rotation of said brushes being opposite to that of the direction of work feed.
22. In a machine of the class described, in combination, fluid-applying means, means for feeding a shoe sole into contact with said applying means, and an adjustable, resiliently mounted plate arranged to contact with the upper surface of the sole for directing the sole into close contact with the applying means during the feeding movement.
23. In a sole coloring machine, in combination, a color-applying brush rotatable on a substantially horizontal axis, means for feeding a sole into tangential contact with the surface of the brush, and a plate contacting with one surface of a sole so fed for guiding said sole to said brush and for holding the other surface thereof in close operative contact with the brush.
24. In a machine for coloring soles, fluid-applying means, means for feeding a sole toward the applying means, a work table extending between said feeding means and applying means and a hold-down plate arranged above said table and resiliently pressed toward the same.

In testimony whereof, I have signed my name to this specification.

HERBERT R. WESTOVER.
